COMBINED BRUSH AND COMB OR THE LIKE

Eric Dent, 21 Dale Ave., Toronto, Ontario, Canada

Filed June 12, 1961, Ser. No. 65,549

Term of patent 14 years

(Cl. D86—10)

FIG. 1 is a perspective view of the combined brush and comb;

FIG. 2 is a side view thereof;

FIG. 3 is a bottom view of the same; and

FIG. 4 is a top view of the combined brush and comb. The essential features of the design reside in the portions shown in full lines on the drawing.

I claim:

The ornamental design for a combined brush and comb or the like, as shown and described.
